UNITED STATES PATENT OFFICE.

WILLIAM H. FITZHUGH, OF BAY CITY, MICHIGAN.

ELECTRIC-ARC LAMP.

SPECIFICATION forming part of Letters Patent No. 678,386, dated July 16, 1901.

Application filed May 11, 1901. Serial No. 59,720. (No model.)

To all whom it may concern:

Be it known that I, WILLIAM H. FITZHUGH, a citizen of the United States, residing at Bay City, in the county of Bay and State of Michigan, have invented certain new and useful Improvements in Electric-Arc Lamps; and I do hereby declare the following to be a full, clear, and exact description of the invention, such as will enable others skilled in the art to 10 which it appertains to make and use the same.

This invention relates to means for converting open-arc lamps of the ordinary type into inclosed lamps, and has for its object to provide a simple and inexpensive device which 15 can be attached to existing lamps for inclosing the arc in a globe yieldingly held in place by a frame which does not interfere to any appreciable extent with the radiation of light from the arc and can be quickly swung out 20 of the way to permit removal of the globe when the lamp is to be trimmed.

Another object is to provide a device for supporting the globe which will hold it in place with even and uniform pressure regardless of any small unevenness or irregularity. 25

A further object is to provide a waterproof cap through which the carbon slides that will carry moisture away from the opening, preventing it from entering the globe.

30 My invention is illustrated in the accompanying drawings, in which—

Figure 1 is a partial front elevation, partly sectional. Fig. 2 is a partial side elevation showing the frame swung clear of the globe 35 and the globe removed from the lamp. Fig. 3 is a sectional detail of the globe-supporting device, the spring being omitted. Fig. 4 is a diametral section of the frame-supporting flange.

40 As is clearly shown in the drawings, the device consists in depending rods A, secured at their upper ends to the lamp-operating mechanism (not shown in the drawings) and carrying a flange B at their lower ends. Pivotally secured to the under side of the flange B 45 is a U-shaped frame or arm C, which normally hangs in a vertical position, but can be swung to a horizontal position for removing the globe. An annular globe-retaining flange 50 B' is formed on the under side of the flange

B and receives the upper open end of the globe D. The lower end of the globe carries a projection D', which is normally supported by a cup E, having a downwardly-projecting central spindle E' and an exterior cylindrical shell E². The lower end of the spindle E' is either spherical, cylindrical, or coned. A corresponding depression is formed in the upper end of the supporting-spindle F, which is adjustably mounted in the lower end of the U-shaped bracket C. This supporting-spindle carries a horizontal flange or equivalent projection near its upper end, and a compressible spring G is interposed between this flange and the under side of the cup E to press the latter 60 upwardly. The shell E² conceals the spring and protects it from the weather. The lower end of the spindle F rests upon a thumbscrew H, by which its vertical height can be 65 adjusted.

The mouth of the globe D is preferably faced off by grinding or otherwise, so as to form a comparatively tight joint with the under side of the flange B. The globe is held in place by the upward pressure of the yielding spring G. It will be noticed that any unevenness in the top of the globe-flange or in the surface of the flange B is compensated for by the pliant mounting of the frame C and of the cup E, which coact to produce a 75 practically uniform upward pressure of the globe-flange upon the flange B and prevents straining the globe unevenly. The spring G, furthermore, permits the cup E to yield vertically a sufficient amount to compensate for 80 the expansion of the globe when heated.

A ring of packing B³ can be inserted between the flange of the globe and the under side of the flange B, if desired.

In order to prevent water from entering 90 the globe through the carbon-holes, I form the flange B with a raised central portion B², through the highest part of which is the carbon-opening. Any moisture striking the upper surface of the flange B will flow away 95 from the carbon instead of into the opening.

By the means above described I have produced a simple, compact, and inexpensive inclosing device for arc-lamps which can be readily applied to lamps of the type in com- 100

mon use, is easily operated to remove the globe when renewing the carbons, and does not obstruct the light.

What I claim as my invention, and desire 5 to secure by Letters Patent, is—

1. In combination with an arc-lamp; a horizontal flange suspended from the lamp-casing; a depending **U**-frame pivoted at its upper ends to the under side of said flange; a globe 10 having a single opening at its top and a central projection at its bottom; an adjusting-screw through the lower part of the **U**-frame; a vertical spindle resting on the upper end of said screw and slidably mounted in the lower part of the frame; a second spindle 15 above the first spindle; a compressible spring secured to the lower spindle and yieldingly supporting the upper spindle, substantially as set forth.
2. In combination with an arc-lamp; a horizontal flange suspended from the lamp-casing; a depending **U**-frame pivoted at its upper ends to the under side of said flange; a globe 20 having a single opening at its top and a central projection at its bottom; an adjusting-screw through the lower part of the **U**-frame; a vertical spindle resting on the upper end of said screw and slidably mounted in the lower part of the frame, said spindle being cupped at its upper end; a second spindle 25 above said first spindle, having a recess in its upper end to receive the projection of the globe; together with a compressible spring secured to the lower spindle and yieldingly supporting the upper spindle, substantially as set forth.
3. In combination with an arc-lamp; a horizontal flange suspended from the lamp-casing; 30 a depending **U**-frame pivoted at its upper ends to the under side of said flange; a globe having a single opening at its top and a cen-

tral projection at its bottom; an adjusting-screw through the lower part of the **U**-frame; a vertical spindle resting on the upper end 40 of said screw and slidably mounted in the lower part of the frame, said spindle being cupped at its upper end; a second spindle above said first spindle, having a recess in its upper end to receive the projection of the 45 globe; together with a compressible spring secured to the lower spindle and yieldingly supporting the upper spindle, substantially as described and for the purpose set forth.

4. In combination with an arc-lamp; a horizontal flange suspended from the lamp-casing; a depending **U**-frame pivoted at its upper ends to the under side of said flange; a globe 50 having a single opening at its top and a central projection at its bottom; an adjusting-screw through the lower part of the **U**-frame; a vertical spindle resting on the upper end of said screw and slidably mounted in the lower part of the frame, said spindle being cupped at its upper end; a second spindle 55 above said first spindle, having a recess in its upper end to receive the projection of the globe and having a projection on its lower end above the cupped end of the first spindle; together with a compressible spring secured to the lower spindle and yieldingly supporting the upper spindle, substantially as described and for the purpose set forth.

In testimony whereof I affix my signature in presence of two witnesses.

WILLIAM H. FITZHUGH.
